UNITED STATES PATENT OFFICE.

JOHN R. SUTTER, OF KANSAS CITY, MISSOURI.

LANTERN.

1,143,238.

Specification of Letters Patent. Patented June 15, 1915.

Application filed May 11, 1914. Serial No. 837,781.

To all whom it may concern:

Be it known that I, JOHN R. SUTTER, a citizen of the United States, residing at Kansas City, in the county of Jackson and

5 State of Missouri, have invented certain new and useful Improvements in Lanterns; and I do declare the following to be a full, clear, and exact description of the invention, such as will enable others skilled in the art 10 to which it appertains to make and use the same, reference being had to the accompanying drawings, and to the letters and figures of reference marked thereon, which form a part of this specification.

15 My invention relates to lanterns, and more particularly to a lantern especially adapted for burning gasolene, or like fuel, wherein burner and generator members are supported by a fuel supply tube and spaced 20 from the storage vessel; the principal object of the invention being to provide a structure of this character wherein the globe and upper frame parts are supported directly from the base of the lantern when 25 the latter is either resting on its base or swung from the handle, and thereby relieve the burner tube of the weight of the superimposed parts.

In accomplishing these objects I have 30 provided improved details of structure, the preferred forms of which are illustrated in the accompanying drawings, wherein:—

Figure I is a perspective view of a lantern constructed according to my invention. 35 Fig. II is a plan view of the globe base; the globe being removed and the supporting standards and burner tubes being in section; the view illustrating one of the damper plates partially open. Fig. III is 40 an inverted plan view of the globe base, the supporting standards and burner tubes being in section. Fig. IV is a detail elevation of one of the supporting standards, partly in section, and illustrating the mounting of 45 the globe base and handle. Fig. V is a detail view, showing manner of clamping the top member on the supporting standards.

Referring more in detail to the parts, 1 designates the base of the lantern, which 50 forms a tank for containing the liquid fuel, and 2 are standards which rise from opposite positions on the tank to support the globe about the burner parts.

Each of the standards 2 comprises a rod 55 3 which is threaded into a nut 4 that is preferably welded, or otherwise perma-

nently secured, to the top of the tank 1, and sleeves 5—6, which inclose the rod and support the base and top 7—8 of the globe casing.

The globe base 7 preferably comprises 60 ears 9 which project beyond the edge thereof, and are provided with apertures 10 of such diameter that they may slide freely over the rods 3 and seat on the lower sleeve 5, and the top 8 is of greater diameter than 65 the base and provided with apertures 11 which also slide on the rod 3 and are seated on the tops of the outwardly projecting ears 12.

The outwardly projecting ears 12, rest on 70 the upper ends of sleeves 6, and are provided with apertures 13 therein for receiving the rods 3, and with upturned outer ends containing transverse apertures 14 for 75 pivotally mounting the inturned ends 15 of a handle 16 from which the lantern may be swung.

The tips of the inturned ends 15 of the handle are provided with nuts 17 for locking the handle to the standards, but which 80 do not interfere with the free pivotal movement of the inturned ends in their mountings.

The base 7 and top 8 have facing edge 85 flanges 18 for confining a globe 19, and the base 7 is cut out at the center to form a recess 20 through which the supply tube and regulator valve may be projected.

Mounted on the tank 1 and projecting 90 into the globe casing, through the recess in the base 7, is a supply tube 21, having a valve 22 below the base, and provided, within the globe, with a generator 23. The generator may be of any suitable construction, and is controlled by a regulator of any ordinary type, having a stem 24 projecting downwardly through the hollow center of the base, and provided with a handle member 25, so that both the flow of liquid fuel and 95 the vapor may be controlled from beneath the globe. The top of the globe comprises a dome 26, having suitable air intake ports 27 and a cap 28, which may be adapted for providing a down-draft. The generator 100 also comprises an air supply tube 29, which extends downwardly through an aperture 30 in the base 7.

Threaded into the upper end of the tube 21 is an upwardly extended rod 31 which 110 projects through an aperture 32 in the center of the cap 28 and carries a tightening nut

33, by which the top 8 is clamped firmly against ears 12, so that the upper sleeves 6 are pressed downwardly onto the top of base ears 9 to hold the sleeve and casing members firmly in place.

Pivotedly mounted on the base 7 are damper-plates 32, which are adapted for closing or regulating the hollow center of the base and are provided with apertures 33 and 10 sockets 34 for admitting air to the interior of the globe when the plates are shut, and for providing a close fit around the generator and supply tubes. The damper plate is also adapted for manipulation when the 15 lantern is to be lighted, and is held in close relation to the base and adapted for guided travel thereover by pin and slot connection 35—36 with the base.

It is apparent that with a lantern of this 20 construction, the globe parts are supported entirely from the tank base when the lantern is not in use, and that when in use, the entire structure is supported from the base through the connection of the handle with 25 the side standards 2, so that the only weight placed on the fuel supply tube is that of the burner and generator. This arrangement not only forms a very substantial and compact structure, but also obviates derangement of the burner and generator by the strain which would be placed thereon if the 30 tank and other parts were supported from the supply tube or burner, as would be the case if the globe were mounted on the tube and the handle connected with the globe or 35 its cap. The construction also adapts the device for proper regulation and draft, and the arrangement of the parts, as described, provides a lantern having a neat and attractive appearance.

Having thus described my invention, what I claim as new therein, and desire to secure by Letters-Patent, is:

1. A lantern comprising a base, standards 45 rising from the base, a burner closure comprising a globe and spaced base and top members mounted on the standards and adapted to support the globe, a supply tube rising from the base, burner members mounted on said supply tube within the 50 globe, and regulating members for the supply tube and burner located between the lantern and globe bases.

Copies of this patent may be obtained for five cents each, by addressing the "Commissioner of Patents, Washington, D. C."

2. A lantern comprising a base tank, rods fixed on and rising above the base tank, upper and lower sleeves mounted on said rods, a globe base having apertured portions slidably mounted on the rods and supported on said lower sleeves, ears mounted on the upper sleeves, a globe top slideable on the rods and supported on said ears, a handle pivotally mounted on said ears, a globe mounted between the globe top and base members, a supply tube mounted on the tank, and a burner mounted on the supply tube within the globe.

3. A lantern comprising a base, standards rising from the base, a burner closure comprising spaced base and top members mounted on the standards, and a globe supported between said base and top members, a supply tube rising from the base, burner members mounted on said supply tube within the globe, a rod on said supply tube extending through the top of the globe, and a nut on said rod for clamping the globe in position.

4. A lantern comprising a base tank, standards rising from said tank, a handle on said standards, a burner closure supported on said standards and comprising top and base members and a globe supported between said base members, a fuel supply pipe rising from said tank and projecting into said burner closure, a burner on said pipe and a damper on said base member surrounding said fuel supply pipe.

5. A lantern comprising a base tank, standards rising from said tank, a handle on said standards, a burner closure mounted on said standards and comprising top and base members, a fuel supply pipe rising from the tank and projecting into said closure, a burner on said pipe, a regulating valve on said burner projecting from the lower part of said closure, an air supply pipe for said burner opening through said base member, and an adjustable damper on said base member adapted to close around said fuel supply pipe and regulating valve.

In testimony whereof I affix my signature in presence of two witnesses.

JOHN R. SUTTER.
